Primary Examiner — Calvin E Vansant*Assistant Examiner* — Giang Hoang Tran(74) *Attorney, Agent, or Firm* — Justin Lampel(57) **CLAIM**

The ornamental design for an egg-shaped kiosk, as shown and described.

DESCRIPTION

FIG. 1 is a left side perspective view of an egg-shaped kiosk in accordance with my design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a left-side perspective view of the egg-shaped kiosk in an operational position with an upper portion and an access panel in an open conformation.

The broken lines illustrate portions of the environment or the egg-shaped kiosk which form no part of the claimed design.

1 Claim, 7 Drawing Sheets(56)
